UNITED STATES PATENT OFFICE.

CUTHBERT S. BUTCHART, OF RYE, NEW YORK.

GOLF CLUB.

Application filed June 4, 1926. Serial No. 118,818.

This invention relates to improvements in golf club heads and more particularly to that type known as "drivers", and the invention contemplates an improved construction 5 of such a head which will present various advantages not obtainable or present in such heads as ordinarily constructed.

Golf club heads of the driver type are ordinarily made of wood and so turned, in 10 the process of manufacture, that the grain runs in the general direction of the toe of the head so that the grain is presented side- wise to the driving side of the head. In such a construction, the impact of the driv- 15 ing face of the club head with the ball is to a certain degree cushioned by the lateral compression of the fibers of the wood, but this is undesirable as it, to a degree, mini- 20 mizes the impactive force delivered to the ball, with the result that the ball is not driven as great a distance as it would be if the head possessed no cushioning qualities whatsoever. Therefore, it is one of the ob- 25 jects of the present invention to provide a golf club head so constructed that the full force of the blow delivered to the ball will be effective and there will be no cushioning whatsoever of the impact.

Another disadvantage presented by golf 30 club heads of wood, or more specifically of one-piece wood construction, is that, be- cause of the contour of the head, it is neces- sary to employ some weighting means em- bedded in the head to obtain the proper 35 balance, but the amount of weighting mate- rial employed and the location of the same is a matter requiring considerable experi- ment if the best results are to be obtained. Therefore, the present invention has, as an 40 other important object, to provide a golf club head comprising a shell-like body of one piece of metal, and an impact member housed therein and in the nature of a block 45 of wood so shaped, proportioned, and lo- cated, as to provide for precise balancing and weighting of the head without resort to any of the extraneous weighting and balanc- 50 ing means which have heretofore been em- ployed, the block having the grain running between its opposite faces, one of which 55 faces constitutes the impact or driving face of the club head. In this connection, the invention contemplates the selection of woods of varying degrees of specific gravity, so that the desired weighting of the head as a whole may be obtained, the contour of the

block and its disposition within the head determining the balancing of the head.

Another disadvantage presented by solid 60 wooden golf club heads having wooden shanks or necks, is that the shaft ends must be united thereto by a wrapping or binding in order to effect a secure union of the head to the shaft, but time and labor must be 65 spent in performing this wrapping or bind- ing step, in the course of manufacture, if the connection is to be firm and secure. Therefore, it is another important object of 70 the invention to provide a golf club head consisting, as before stated, of a shell-like body of metal and an impact block or body of wood fitted therein, the shaft receiving neck of the body constituting an integral part of the said metallic shell-like body and being designed to directly receive the end of 75 a metallic shaft, the invention contemplating the provision of means for directly securing the parts together without the employment of any binding at their juncture.

Another object of the invention is to so 80 construct the shell-like body of the head and the impact block and likewise the shaft end of the club that when these parts are assembed, the end of the shaft will con- 85 stitute means for positively preventing any displacement of the impact block with re- 90 spect to the body of the head, thus render- ing it unnecessary to employ any extraneous fastening devices for this purpose and there- 95 by obviating any weakening of the body of the head or the block. In this connection, the invention has as a further object to pro- 100 vide means for securing the end of the shaft in proper position assembled with the neck and body of the head and which means will likewise assist in securing the impact block within the said body of the head.

Another object of the invention is to so 105 interiorly form the shell-like body of the head and so arrange the impact block there- in that there can be no disturbance of the position of the block after it has once been assembed with the body of the head, the construction being such that the insertion 110 of the block into the head is limited pre- cisely to the point where, the block being properly proportioned, the block will be so positioned as to exactly balance the head, so that accurate drives may be made and like- wise so that the full impactive force de- livered to the ball will be received by the ball and none of the force lost by any cush-

ioning of the impact. In this connection, the invention contemplates an accurate positioning of the impact block to obtain a precisely and accurately balanced club head, the 5 center of gravity of the head, as a whole, being precisely in a vertical plane with the axis of the shaft with which the head is associated.

A further object of the invention is to 10 provide a golf club head so constructed that it will withstand wear for a greater period of time and more effectually than solid wood heads or heads having the major portion of their surface area of wood, thereby obviating 15 the employment of sole plates, inserts, or any other expedients usually employed to protect the head.

In the accompanying drawings:

Figure 1 is a perspective view of a golf 20 club head of the driver type and a portion of the shaft assembled therewith, constructed in accordance with the invention, the view being taken in a direction looking at the driving face of the head.

Figure 2 is a bottom plan view of the 25 head, a portion of the bottom of the shell body of the head being broken away and a portion being shown in section to better illustrate the construction.

Figure 3 is a vertical longitudinal sectional view taken substantially on the line 30 3-3 of Figure 2, looking in the direction indicated by the arrows.

Figure 4 is a vertical transverse sectional view through the head at the intermediate 35 portion thereof.

The golf club head embodying the invention includes a shell-like body which is indicated in general by the numeral 1 and this 40 body is made of some suitable metal such for example as an aluminum alloy and is integral throughout, the body being provided with an integral neck which is indicated by the numeral 2. The shell-like body 1 is exteriorly of the contour usually given golf club heads of the driver type, and has the usual sole 3, toe 4, and heel 5. The side of the shell-like body which corresponds to the driving face of the head is open and the 45 edges of the walls of the body at this side thereof are located in an inclined plane corresponding to the usual inclination given the driving face of such a club as that referred to. The body 1 is hollow although, 50 as will be observed by reference to the several figures of the drawings, the walls of the body are not of uniform thickness. More specifically, the body is provided interiorly with a seating recess or socket which is indicated by the numeral 6 and which opens 55 through the driving face of the body and is, from front to rear, of a uniform contour substantially identical with the contour of the driving or impact face of the ordinary 60 golf club head as clearly shown in Figure 1

of the drawings. This recess or socket 6 is intended to accommodate the impact and weighting and balancing block which will hereinafter be more specifically described, and it will be observed that said socket 70 extends into the body to a point more than midway between what may be considered as the driving face of the body and the back 5', the inner end of the socket being defined by a shoulder 7 which is produced by forming 75 a cavity 8 in the body at the back portion thereof. The shoulder 7 is continuous as will be observed by a comparison of Figures 2 and 4 of the drawings, and occupies a vertical plane parallel to the vertical plane occupied by the axis of the club shaft, or, the axis of the neck 2.

The member which constitutes at once the impact, weighting, and balancing member of the club head, is indicated in general by 80 the numeral 9, and this member comprises a block of hard and tough wood, such for example as ash, elm, beech, persimmon, dogwood, lignumvitæ, etc., which is circumferentially of a contour corresponding exactly to 85 the contour of the inner surface of the walls of the socket 6 and of dimensions to fit with such exactness in the socket as to require it to be forced by pressure into place within the socket at the time the parts are assembled in the course of manufacture. The block has an inclined face 10 which may be of slightly curvilinear contour in a longitudinal direction, or entirely flat, as may be desired, and the opposite face of the 90 block, which is indicated by the numeral 11, is so disposed that when the block is in position within the shell-like body of the head this face will occupy the same plane as the shoulder 7 and, in fact, will marginally not 95 only snugly contact or abut the said shoulder but will preferably be united thereto by some suitable adhesive, as indicated by the numeral 12. It will be observed by reference to the drawings, that the grain of the 100 wood block comprising the member 9 runs longitudinally between the faces 10 and 11 of the block so that the grain is presented endwise at the said face 10, which face is very smoothly dressed and finished and is 105 flush with the margins of the walls of the socket 6 at the open side of the socket, as clearly shown in Figure 4 of the drawings. At this point, it will be evident that when the block is forced into place within the 110 socket 6 in the head of the club, in position with its face 11 abutting the shoulder 7, there can be no further movement of the block into the body of the head, regardless 115 of the impactive forces to which the block is subjected. It will likewise be evident that inasmuch as the grain of the block runs longitudinally between the faces 10 and 11 thereof and, therefore, directly in a line with the impactive force to which the block is 120 125 130

subjected when the driving face 10 impacts the golf ball, there is no appreciable vibration of the fibers of the block of such nature as would tend to cushion said force and impair the driving force of the blow as is the case where the grain, in the ordinary golf club head, runs substantially parallel to the impacting face of the head. It will be observed, particularly by reference to Figures 2 and 4 of the drawings, that the center of gravity of the member 9 is directly in the vertical plane of the axis of the neck 2 and consequently in the same plane as the axis of the shaft of the club so that the head is precisely balanced. The back portion of the body 1 of the head, being hollow and likewise of an aluminum alloy which is comparatively light, does not in any way overbalance the head of the club, the mass of the block 9 and the disposition of this block within the body 1 of the head and with respect to the axis of the shaft of the club serving to effect this precise balancing of the head.

It will be understood that inasmuch as the block 9 is tightly fitted into the socket 6, no moisture can enter the interior of the shell-like body 1 of the head to cause deterioration of the said block, the impacting face of the block being preferably finished with a waterproof varnish or other finishing material.

The bore of the neck 2 is indicated by the numeral 13 and the said bore is continued in a downward direction through the inner end of the head of the club and opens through the under side of the said head at the heel thereof, as clearly shown in Figures 2 and 3 of the drawings. The line of extent of the bore 13 of the neck 2 is such that at its lower end its forward side opens into the socket 6, and the block 9 is formed with a transversely curved recess 14 in its corresponding end, the curvature of the recess conforming to the contour of the wall of the bore. The shaft of the club, which is indicated by the numeral 15, and which is of metal, is fitted into the bore 13 and extends to the extreme lower end of the bore where the said end of the shaft is beveled so as to be flush with the under side of the body 1. It will be observed that a portion of the lower end of the shaft 15 fills the recess 14 so that in this manner the said end of the shaft acts as a key to securely lock the block 9 against any outward displacement from the socket 6. A plug 16, preferably of wood, is fitted into the lower end of the shaft 15, and a pin or other suitable securing element 17 is driven through the lower end of the stem 2, through diametrically opposite openings 18 in the said lower end of the shaft, through the plug 16, and into the block 9, thus securely anchoring the said end of the shaft in place and likewise further securing the block 9 so that it cannot

become outwardly displaced from the socket 6. Not only does the pin 17 serve to secure these parts together in the manner stated, but it also serves to secure the shaft in the neck without the employment of any binding means.

It will be understood that the formation of the cavity 8 in the back of the club head serves to reduce the weight of this portion of the head so that the member 9 may be depended upon to serve the purpose of the weighting and balancing medium of the head and, therefore, by a selection of woods such as those heretofore referred to and having different specific gravities, a complete head may be produced having precisely the desired weight and in each and every instance the head will be precisely balanced.

Having thus described the invention, what I claim is:

1. A golf club head comprising an integral metallic body having a socket opening through its driving face and provided interiorly with a shoulder extending continuously about the wall of the socket, the said body being recessed beyond the said shoulder to minimize weight of material, and a combined, weighting, balancing and impacting body of wood within the socket having a side marginally abutting the said shoulder.

2. A golf club comprising a head consisting of an integral metal body having a socket opening through its driving side, a tubular neck integral with and extending from the body, a combined weighting, balancing and impacting body within the socket having a recess registering with the bore of the said neck, and a shaft fitting into the said neck and engaging in the recess in the impacting body and, by such engagement, securing the impacting body in the socket.

3. A golf club comprising a head having a socket therein and provided with a tubular neck extending therefrom, an impacting member within the socket having a recess registering with the bore of the neck, and a shaft fitted into the bore of the neck and engaging in the recess whereby to secure the said body within the socket.

4. A golf club comprising a head consisting of an integral metal body having a socket opening through its driving side and provided with a shoulder extending about the wall of the socket, a tubular neck integral with and extending from the body, a combined weighting, balancing and impacting body within the socket having a recess registering with the bore in the said neck, the body at its inner face abutting the said shoulder, and a shaft fitted into the said neck and engaging in the recess in the impacting body and, by such engagement, securing the impacting body in the socket.

5. A golf club comprising a head consisting of an integral metal body having a

socket opening through its driving side, a tubular neck integral with and extending from the body, a combined weighting, balancing and impacting body within the socket having a recess registering with the bore of the said neck, a shaft fitting into the said neck and engaging in the recess in the impacting body and, by such engagement, securing the impacting body in the socket, and a securing element driven through the said shaft and the wall of the body of the head and into the impacting body.

In testimony whereof I affix my signature.
CUTHBERT S. BUTCHART. [l.s.]
